Atty.

UNITED STATES PATENT OFFICE.

TERRENCE F. McGOWAN, OF BOSTON, MASSACHUSETTS.

EDUCATIONAL GAME.

Application filed April 11, 1925. Serial No. 22,444.

To all whom it may concern:

Be it known that I, TERRENCE F. McGOWAN, a citizen of the United States of America, and a resident of Boston, in the county of Suffolk and Commonwealth of Massachusetts, have invented certain new and useful Improvements in Educational Games, of which the following is a specification.

10 This invention relates to a game, and more particularly to a game having qualities for the advancement of the education of the players.

15 It is an object of the invention to produce a simple, and easily understood and learned, game, which is educational in character and which may be applied in many ways and cover a variety of interesting and instructive subjects.

20 A further object of the invention is to so devise a game of the above class that a play by one person indicates the move or action to be taken by that person and also dictates the move or action of the next player.

25 Other objects of the invention will be fully understood from a description of the drawings and the claims hereinafter given.

Of the drawings:

Figure 1 represents a plan view of a game board arranged to embody the invention.

Figures 2 and 3 are details of certain portions of the game apparatus shown in Figure 1.

Figure 4 is a view similar to Figure 2 on a slightly enlarged scale, and having a certain portion thereof broken away for clearness.

Figure 5 is a part section taken on the line 5—5 Figure 1, and on an enlarged scale.

40 Like characters represent like parts throughout the several figures of the drawings.

Referring to the drawings:

The drawings herewith illustrate the invention in one of its simple forms, but it will be understood that this is merely for the purpose of explanation as it is possible to make various changes in the subject upon which the game is played and the manner of playing it and the complexity thereof with

out departing from the spirit and scope of the invention.

In the present instance it is preferred to arrange the majority of the game parts on a board 10, while other parts such as markers 11 may be detached for the purpose of shifting them about the board.

As the game is intended primarily as an educational amusement, it is preferred for purposes of explanation to illustrate it as being played on a territory familiar to the players, and in view of that fact an indication of the map of the United States is chosen as a fitting subject and ground for the game.

Let it be supposed that two players have previously agreed upon the rules and have entered a contest as regards time, distance and capitals or cities visited or touched upon a supposed tour of the United States, which of course is subject to the plays or the result of plays made by each one in turn, and that each of the players starts at a given point such as the capital city of Massachusetts, Boston, as indicated at B, and that the one reaching the Pacific coast or a given point thereon first shall be declared the winner.

The markers 11 which may be pins or other suitable devices will be positioned in close proximity to the capital city or other point from which the contest starts, and the first player will cause the scalloped disk 12 to be rotated about the pivot 13, and before the start of play will see that the flaps 14 of the said disk are each opposite a numbered space of the dial 15 as seen in Figures 1, 2 and 3.

This move is made so that previous knowledge of the location of moves or plays that might be made will be offset.

The first player now turns back one of the flaps 14 as seen in Figure 3 which happens to be the flap that at that time is opposite the numeral 5, and inside the inner circle or disk 16 now exposed, a character appears which happens to be the letter "S," indicating to that player that the first move for his marker 11 is in a southerly direction and to the nearest State, State capital or city as previously agreed upon which

we will say in the present instance is Providence, the capital of Rhode Island.

Upon the reverse side of the turned flap 14 another character appears which happens 5 to be the numeral 12 indicating to the next player that his move or play is to turn back the flap opposite to that number on his portion of the game board as seen in Figure 2, and which exposes for his instruction the 10 direction of travel he shall take, which happens to be the letter "E," indicating that he must travel east, and since movement in that direction would take him into the ocean he will be considered as left at his starting 15 point and not having made progress for that play.

When the second player has turned back the flap as just explained, the reverse side thereof exposes a numeral as 7, see Figure 2, 20 which indicates to his opponent the direction of travel he must or may assume, which in this instance is "Travel any Direction" as would appear as the flap opposite that number shows, by viewing Figure 4, which instruction would naturally be followed to the 25 best advantage of that player.

In the above manner the game may progress until one or the other of the players first attains the object in view.

If agreed upon, the means of transportation may be included in the game, as for instance, in the case of the first player's turning back the flap opposite the numeral 5, his direction of travel is indicated as "S" 35 or south, and by reference to the transportation indicator T it will be seen that under the numeral 5 appears the word "Boat" which indicates that the player must travel by boat and if such method of travel is impossible he will be obliged to remain at the 40 starting point until such time as his instructions dictate either land or air transportation.

In the present instance it is possible for 45 the player to travel from Boston to Providence by boat and consequently he will take advantage of the opportunity to move from the starting point.

In the event that a player's marker is so 50 located that a play by him calls for movement in a certain direction, and by land, and water intervenes, or must be crossed to arrive at the place or point indicated, the marker will not be moved and the player must wait till such time as the direction and 55 method of transportation are agreeable to such a move.

After each play, and when the player has 60 noted his direction of movement, and the opposing player has also noted his instruction, the flap 14 will be turned to its original position in preparation for use at a later time if the run of the play so decides.

While a map of the United States has 65 been shown as part of the game board, it

will be understood that other maps, pictures or charts might be used and need not be affixed to the board, and while a certain set of means of transportation has been shown herein, it will be understood that changes 70 might be made therein to suit the map or other game subject that may be used.

Having described the invention I claim:

1. A game having an educational subject 75 as a basis of play, and means, to be chosen at random and operated by the first player, whereby said player receives instruction as to his first move, and means exposed by the said first means when operated whereby the next player receives instructions as to his first move; and means to mark each move of a player.

2. A game having an educational subject 80 as a basis of play, and means operable by a player whereby instructions are received by him as to his first move, and at the same time partial instructions to be followed by the next player is exposed; and means to mark the moves of each player.

3. A game having an educational subject 85 as a basis of play; means provided for each player and operable thereby, whereby each player in turn will receive instruction as to his move, and at the same time expose to 90 view instruction for the following player, which instruction when followed reveals further instruction for said following player and at the same time reveals instruction for the next following player; and means to mark the moves of each player.

4. A game having an educational subject 95 as a basis of play and comprising a board having provision for the likeness of an educational subject thereon, and having an indicator device for each player, said device being arranged to expose to the player the move to be made by that player and to indicate the first move to be made by the following player, said device being arranged in 100 a shiftable manner; and means to mark the progress of each player.

5. A game having an educational subject 105 as a basis of play and comprising a board having provision for the likeness of an educational subject thereon, and having an indicator device for each player, said device being arranged to expose to the player the move to be made by that player, and to indicate the first move to be made by the following player; and an indicator arranged in conjunction with each indicator device to 110 dictate the mode of supposed travel of the players in turn.

6. A game having an educational subject 115 as a basis of play and comprising a board having provision thereon for the likeness of an educational subject, and having a rotatable disk for each player, each disc having a plurality of flaps thereon, said flaps being arranged to conceal direction characters,

and to be aligned with spaced characters that are exposed to the view of the players, and to be turned to expose said direction characters to view; and means to mark the progress of each player.

7. A game of the class described comprising a board having a map thereon and a plurality of indicators having flaps thereon, said flaps normally concealing direction characters arranged to be exposed to view

upon turning said flaps back, other indicating means arranged to be aligned with said flaps; indicating means arranged to dictate modes of transportation according to the character appearing opposite the flap turned back; and means to mark the progress of the players.

Signed by me at Boston, Mass., this 7th day of April, 1925.

TERRENCE F. McGOWAN.
